[57] **CLAIM**

The ornamental design for an tool handle with inter-
changeable shovel blade, as shown and described.

DESCRIPTION

FIG. 1 is a top, rear, right side perspective view of a
tool handle with interchangeable shovel blade showing
my new design;

FIG. 2 is an exploded perspective view thereof;

FIG. 3 is a right side, elevational view thereof, showing
my new design, with the left side constituting a mirror
image of the right side; and,

FIG. 4 is a rear elevational view thereof.

The claimed design is shown detached in FIG. 2 for
clarity of illustration. The front view of the handle
portion of the claimed design is a mirror image of the
rear view and the front view of the shovel blade is
unornamented.
